STEERING GEAR

Application filed February 18, 1931. Serial No. 516,627.

The present invention relates to marine steering gear.

In marine steering gear of the screw type which is in common use for small craft, considerable difficulty is often encountered in assembling the gear on the rudder post. The entire gear is lowered onto the rudder post and since the top of the rudder post is not usually in a conveniently accessible position, it may be a matter of considerable trouble to insert the key or other means by which the rudder head is secured to the post.

The object of the present invention is to provide a simple and rugged steering gear which has provision for convenient attachment to or removal from the rudder post.

With this object in view, the present invention consists of a steerer having a separable rudder head, a part of which is adapted for convenient attachment to the rudder post without the necessity for handling the remainder of the equipment. The rudder head may thus be firmly secured to the rudder post by a blind keyway or by other suitable attaching means, after which the operating mechanism may be secured to the rudder head. This construction makes for quick attachment or removal of the entire steering gear whenever such operations are necessary.

Other features of the invention consist in certain novel features of construction, combinations and arrangement of parts hereinafter described and particularly defined in the claim.

In the accompanying drawing, Fig. 1 is a plan view of the preferred form of steerer embodying the features of the present invention; Fig. 2 is a side elevation of the steerer shown in Fig. 1; and Fig. 3 is a detail view on line 3—3 of Fig. 1.

The illustrated embodiment of the invention comprises a double screw 4 of the usual form provided with both right and left hand threads indicated at 6 and 8 serving to actuate the traveling nuts 12 which are received thereon. One end of the screw is journaled in a bearing 14 and the other end is provided with a keyway 16 to receive the steering wheel. The wheel end of the screw

passes through a bearing 18 mounted on the rudder head which is indicated generally at 20. The nuts 12 are connected by links 22 and 24 to opposite sides of the rudder head, whereby upon rotation of the screw, the nuts travel in a direction to rotate the rudder head. Because of the unequal length of the arms 22 and 24 in the particular construction shown, there is necessarily a compensating longitudinal movement of the screw which is permitted by the bearings 14 and 18. The construction thus far described is a common type of steering mechanism useful on craft of small and moderate size.

The rudder head 20 which is attached to the rudder post 26 comprises two separable flanged members, namely, a lower member 28 adapted for attachment to the rudder post and an upper member 30 which is connected to and rotated by the screw. The upper member 30 is provided at opposite sides with bosses 32 upon which the ends of the links 22 and 24 are pivoted. Connected between the bosses is a web 34 which is provided at the center with an opening to receive a stud 36 projecting upwardly from the bearing block 18. As is usual in such steerer constructions, the bearing block 18 has a downwardly projecting stud which is received in an opening 38 in the top of the rudder head.

The lower flanged member 28 of the rudder head comprises a sleeve portion 40 having an internal diameter of the proper size to be received on the rudder post. The rudder post and the sleeve 40 are formed with registering keyways to receive the key 42. As shown in Fig. 3, the keyway of the shaft terminates immediately below the end of the sleeve in order that the key may be securely retained in position. The member 28 is formed with a flange 44 which is attached directly to a flange 46 of the upper member by a plurality of bolts 48. The upper member 30 is provided with a central boss 50 which is received in a central recess of the lower flange member. Inasmuch as the thrusts imparted by the links 22 and 24 are not exactly balanced, the boss 50 serves to relieve the stress on the attaching bolts 48. This is a particularly desirable feature not

only in a steerer of the type shown in the drawing, but also in the single screw type which applies an unbalanced thrust to only one side of the rudder head.

- 5 In assembling the steerer, the lower part 28 of the rudder head is fitted on the rudder post. The key 42 is forced into the registering keyways, thus firmly securing the rudder head to the shaft. The entire steerer is
10 now mounted on the flanged member 28 and the two flanges 44 and 46 are secured together by the bolts 48. Since the upper part of the rudder head completely covers the shaft, a blind keyway is provided which assures against loss or accidental removal of the key. It will be seen that if an attempt is made to provide a blind keyway in a steerer of the ordinary type, considerable difficulty is met with in assembling the apparatus on
15 the rudder post.

The present invention is not to be considered as limited to a construction in which the rudder head is keyed to the rudder post. In constructions employing wood rudder posts
20 wherein the connection between the post and the head is ordinarily made through cooperating lugs or projections, the present invention also offers the same advantages in that the lower flange of the rudder head may be conveniently attached to the post before assembly of the remainder of the gear. In its broader aspects, therefore, the present invention contemplates a separable or two-part rudder head, the lower part of which has provision for secure attachment to the rudder post and the upper part of which may thereafter be secured to the lower part, forming a means for transmitting motion from the actuating mechanism to the rudder.

25 40 Having thus described the invention, what is claimed is:

In marine steering gear, the combination with screw actuating means of a rudder head having separable upper and lower flanged members, a link connecting the screw with the rudder head, one having a boss received in a recess of the other to take the unbalanced thrust of the link, means for attaching the lower member to a rudder post, and means
30 35 45 50 for securing the flanged members together after attachment of the lower member to the rudder post.
